(57) **CLAIM**

The ornamental design for a high voltage electric power switch with turned-out line taps, as shown and described herein.

DESCRIPTION

FIG. 1 is a perspective top view of a high voltage electric power switch with turned-out line taps.

FIG. 2 is a front side view of the high voltage electric power switch with turned-out line taps.

FIG. 3 is a right side view of the high voltage electric power switch with turned-out line taps.

FIG. 4 is a left side view of the high voltage electric power switch with turned-out line taps; and,

FIG. 5 is a top view of the high voltage electric power switch with turned-out line taps.

The broken line portion of the figure drawings is included to show portions of the article that form no part of the claimed design.

1 Claim, 2 Drawing Sheets
